UNITED STATES PATENT OFFICE.

FRIEDRICH J. SALZER, OF ERIE, PENNSYLVANIA, ASSIGNOR OF ONE-FOURTH TO
FRANK SALZER, OF ERIE, PENNSYLVANIA.

TOBACCO-STRINGING MACHINE.

1,208,383.

Specification of Letters Patent. Patented Dec. 12, 1916.

Application filed August 17, 1914. Serial No. 857,254.

To all whom it may concern:

Be it known that I, FRIEDRICH J. SALZER, a subject of the Emperor of Austria-Hungary, residing at Erie, in the county of Erie 5 and State of Pennsylvania, have invented certain new and useful Improvements in Tobacco-Stringing Machines, of which the following is a specification.

An object of my invention is to provide 10 a machine for stringing tobacco which is so arranged that the separate leaves or stalks of the tobacco plant may be threaded onto a cord to be spaced at a predetermined distance apart so that the cord or string may 15 be stretched in the drying shed or room and the plants or leaves will be suspended to permit a free circulation of air on all sides to accomplish a uniform curing and to prevent tobacco mold or stem rot.

20 A further object is to so construct the machine that the power driving means thereof may be kept constant and the operation of the working parts is substantially continuous.

25 Yet another object is to provide means by which the leaves or stalks are threaded onto the needle and to so form said parts that each leaf or plant is impaled through the fibrous stock and is made secure against 30 displacement.

35 A still further object is to provide means arranged to maintain the needle at a fixed point while the means by which the stalks are threaded onto the needle are permitted to have movement with respect thereto.

With other objects in view, which will be referred to, my invention consists in the peculiar combination and novel arrangement 40 of parts, such as will be hereinafter more fully described in connection with the accompanying drawings and more particularly pointed out in the appended claims.

In the drawings:—Figure 1 is a view in side elevation with parts of the operating mechanism thereof broken away to more clearly illustrate the relative positioning of the several coöperating mechanisms. Fig. 2 is a view in front elevation of the machine. Fig. 3 is an enlarged detail view with parts 50 thereof shown in section to illustrate the main operating parts of the machine. Fig. 4 is a horizontal sectional view taken on the line 4—4 of Fig. 1. Fig. 5 is a similar sectional view taken on the line 5—5 of Fig. 1.

Fig. 6 is a view in side elevation of the means 55 by which the needle is maintained in its stationary position and with the operating mechanism thereof also shown. Fig. 7 is a transverse sectional view taken on the line 7—7 of Fig. 6. Fig. 8 discloses a similar 60 sectional view on the line 8—8 of Fig. 6. Fig. 9 is a fragmentary view in top plan of a portion of the notched operating wheel. Fig. 10 is a view in edge elevation of the structure disclosed in Fig. 9. Fig. 11 is a 65 view in transverse section on the line 11—11 of Fig. 9 with a leaf illustrated in the relation in which it will be placed with respect to the leaf-holding finger. Fig. 12 is a transverse vertical sectional view taken on 70 the line 12—12 of Fig. 9 and looking in the direction indicated by the arrow. Fig. 13 is an enlarged detail view of a portion of the mechanism illustrated in Fig. 5. Fig. 14 is a detail view to better illustrate the structure 75 of the stringing needle.

The base 1 of the machine has the standard 2, 2 mounted thereon near one end and adjacent the center, and the cross members 3 and 4 secured transversely across the base 80 members between the standard 2 forms a supporting structure upon which the table top 5 is mounted. A carrying arm 6 is rigidly mounted on the table top 5 and is shaped to overhang the projecting portion 85 of the base member 1.

A power shaft 7 is revolvably mounted in bearings carried by the cross members 3 of the supporting structure and as a means of transmitting power to this shaft, a fly wheel 90 8 is secured to the inner end thereof and has the eccentrically mounted knuckle pin 9 carried thereon to be connected by a pitman 10 with the treadle 11 hinged at 12 to one of the base members 1 to have swinging movement 95 transmitted thereto by the foot of the operator and in consequence to cause a rotation of the shaft 7 which rotation is maintained constant by the fly or balance wheel 8. A pulley wheel 13 is secured on the power shaft 7 100 and a belt 14 is passed over this pulley wheel and over the main pulley 15 which is loosely mounted on the shaft 16 journaled in the carrying arm 6 to lie in the same general plane as the power shaft 7. At the end of 105 the carrying arm 6, stud shaft 17 is secured to depend in a downward direction. A bevel gear wheel 18 which is preferably made of a

large diameter, although the size of the wheel may be varied to suit varying operating conditions, is revolubly mounted on this stud shaft 17 and a bevel gear 19 secured on 5 the inner end of the shaft 16 meshes with the teeth of the carrying gear 18, a clutch 20 being provided to be shifted by the clutch lever 21 to a position to secure the pulley wheel 15 to transmit a driving motion to this 10 shaft 16 upon the rotation of the power shaft 7. By reason of the fact that the belt pulley 15 is loosely mounted on the shaft and the clutch operating levers 21 is positioned at a point to be readily grasped by the 15 operator, the power shaft or drive shaft 7 may be constantly rotated during the normal operation of the machine either by the treadle mechanism as hereinbefore described or by a connection with an independent 20 source of motive power and the rotation of the bevel gearing wheel 18 can be controlled at the will of the operator.

The spacing blocks 22 are positioned at equi-distant points to project from the lower 25 side of the carrying wheel 18 and a notched cam wheel 23 is secured to these spacing blocks to be in concentric arrangement with respect to the rim of the carrying wheel. The cam or operating wheel 23 has the 30 notches 24 provided around the outer peripheries thereof and similar notches 25 are spaced to be radially opposite around the inner circumference of the operating wheel 23. As better illustrated in Fig. 9, the notches 35 24 and 25 of the operating wheel 23 are made sharp on their forward edge and the rear edge of each notch is made on an incline to provide a not-too-sharp ascent to the inner and outer circumferential edges of the operating 40 wheel. Adjacent each pair of the radially aligned notches 24 and 25, a leaf-holding finger 26 is mounted on the lower side of the operating wheel, and each of these leaf-holding fingers 26 is grooved vertically 45 along its forward side as at 27 so that the stem of the leaves or the stock of the plant will be received therein in the relation illustrated in Fig. 11. Each of the leaf-holding fingers 26 has a notch 28 formed adjacent 50 the lower end thereof and these notches are so positioned that a continuous notch is presented around the entire outer circumference of the spaced leaf-holding fingers and the notches, again referring to Fig. 11, are 55 extended past the center of the vertical groove 27.

The skeleton-supporting bracket 29 is secured to the carrying arm 6 to extend toward the stud shaft 17, and a skeleton bracket 60 30 is mounted on the lower end of the stud shaft 17 and is held at a point adjacent the disposition of the bracket 29 by the tightening of the clamp bolt 31 to draw the clamp member 32 of the bracket tight 65 around the stud shaft.

In the operation of my improved machine, it is the intention that a curved piercing needle 33, the structure of which is better disclosed in Fig. 14 be held adjacent the brackets 29 and 30 to move through the 70 notches 28 of the holding fingers 26 at the approximate center of the longitudinal groove 27 and to thus pierce the stems or stock of the leaves or plants to be threaded thereon, the relative disposition of the 75 needle with respect to the holding fingers being illustrated in Figs. 5 and 13. While it is desired to maintain the needle in a stationary position, it will be understood that the movement of the carrying wheel 18 80 causes a rotary motion to be transmitted to the operating wheel 23 and by reason of the fact that the holding fingers 26 depend from this operating wheel and that the plate in which the needle is held is above the lowest 85 point of projection of these fingers 26, some means must be provided which will hold the needle and which will at the same time step over the holding fingers to permit their passage. To accomplish this holding of the 90 piercing needle and to permit the overstepping movement to allow the passage of the leaf-holding fingers, the bearing members 34 and 35 which are substantially duplicates are mounted on the adjacent ends of the 95 bracket members 29 and 30, it being preferable that four or more of these bearing members be located on each of the bracket members and that they be placed to have the bearings thereof in radial alignment with 100 respect to the stud shaft 17. The operating bolts 36 and 37 are slidably mounted in the upper bearing 38 of each of the bearing members 34 and 35, the construction of which is shown in detail in Figs. 6 to 8, inclusive, and these operating bolts have the outer ends thereof beveled at 39 to substantially the same angle as the bevel edge of the notches 24 and 25 of the operating 105 wheel 23. The anchoring bolts 40 and 41 110 are slidably mounted in the bearing 42 provided preferably vertically beneath the slide bearing 38 of the bearing members 34 and 35, and the springs 43 are received around the anchor bolts 40 and 41 to engage at the 115 one end against the abutment pin 44 and at the opposite end against a part of the bearing members so that these bolts will be normally retracted onto the supporting brackets 29 and 30. 120

The pins or friction rolls 45 and 46 are mounted on the inner edge of the operating bolt 36 and the anchor bolt 40 to extend from one side thereof and a rocking lever 47 is pivoted near its approximate center to 125 the bearing members to engage with these pins 45 and 46 so that as the anchor bolt 40 is moved to its retracted position by the tension of the spring 43, the engagement of the pin 46 with the rocking lever 47 will 130

cause the free end of the rocking lever to engage with the pins 45 and will extend the operating bolt 36 to bear against the inner circumference of the operating wheel 23. 5 The pins 48 and 49 are mounted on the operating bolt 37 and the anchor bolt 41 carried by the supporting bracket 29 and the rocking lever 50 is pivoted to the bearing member 35 to engage with each of the pins 48 10 and 49 and as has been hereinbefore set forth, through the tension of the spring 43 to hold the operating bolt 37 in engagement with the outer periphery of the operating wheel 23. 15 The operating bolts 36 and 37 are disposed to lie in the same horizontal plane with the operating wheel 23 and the anchor bolts 40 and 41 are disposed in a plane with the normally held position of the piercing 20 needle 33 which is adapted to work in the notches 28 of the leaf holding fingers 26. This piercing needle 33 is provided along its extent with a plurality of perforations 51 and anchoring pins 52 are carried on 25 the end of the anchoring bolt 41 mounted on the supporting bracket 49 to be engaged through these perforations 51 and to pass into the pin socket 53 of the bolt member 40, this part of the structure being better dis- 30 closed in Fig. 13.

As the operating bolts 36 and 37 are held by the spring tension against the inner and outer circumferential edges of the operating wheel 23, it will be seen that as the notches 35 24 and 25 come into alinement with these bolts, the bolts will be forced or moved into the notches and then as the bolts are retained in a stationary position and the operating wheel 23 is caused to move in a 40 constant path, the bevel faces 39 of the bolts 36 and 37 will engage with and ride up on the bevel edges of the notches 24 and 25 and in this way the anchor bolts 40 and 41 will be alternately moved to the position indicated at *a* and that indicated at *b* in Fig. 45 13 where the anchoring pin 52 will be engaged through the perforation 51 and the anchoring bolts 40 and 41 will be retracted to a position to permit the passage of the 50 leaf-holding fingers 26 therebetween. The operation of the machine is as follows: The string or cord 54 with one end thereof looped is placed to extend as illustrated in Fig. 5 through each of the grooves of the 55 several leaf-holding fingers 26 and the looped end is inserted over the hook end 55 of the piercing needle 33 which is held by two of the anchoring pins being passed through the perforations thereof; the operator then sits adjacent the projecting portions of the base members 1 of the machine and is thus in proximity to the point at 60 which the piercing end of the needle 33 is penetrated through the leaves or stalks, then 65 the clutch lever is shifted to a position to

start the rotation of the carrying wheel 18, the operator places a leaf or plant with the stem or stock in the vertical grooves 27 of the leaf-holding fingers 26 just in advance of the piercing point of the needle 33 and the rotation of the operating wheel 23 from which the fingers 26 depend causes these fingers to be carried so that the needle will penetrate through the stem or stock of the leaf or plant and will pass through the notch 28 of the finger. As the operating bolts 36 and 37 move into and are raised from the notches 24 and 25 of the operating wheel 23, the anchoring bolts 40 and 41 are shifted in their bearings in an opposite direction and the anchoring pin 52 will be alternately engaged through and disengaged from the perforations 51 of the needle 33 and the movement of the anchoring bolts 40 and 41 is so timed that the bolts will be 70 retracted from their engaging position just in advance of each of the holding fingers 26 and will be again permitted to come to the engaged or holding position immediately behind these fingers as they move in the 75 operative path. When this operation has been continued throughout one complete revolution of the carrying wheel 18, the clutch shifting lever 21 will be operated to permit the pulley 15 to run loose on the 80 shaft 16 and thus cut off the power to the bevel gear 19 and stop the rotation of the carrying wheel 18, the string or cord 54 will be unlooped from the hook 55 and can then be disengaged from the notches 28 of the 85 holding fingers 26 and removed to be 90 stretched in the drying house, the drying shed or other suitable point where the curing is to be accomplished, a new cord or string will be looped over the hook 55 and inserted 95 as has been hereinbefore set forth and the 100 operation of the machine will then be completed, by shifting the clutch into operative relation and by the placing of the leaves or stalks by the operator within the grooves 105 provided therefor in the holding fingers. While it will be understood that no specific 110 dimensions are intended to be given here which should be adhered to in the manufacture of the machine, it has been found that very efficient results can be obtained 115 where the operating wheel is provided with some thirty-two of the holding fingers and the needle is made to extend through the space occupied by some six of these holding 120 fingers, then by spacing the parts so that the leaves or plants will be threaded onto the string to be perhaps one and one-half inches apart and using a string of about four feet in length, a result is accomplished 125 which permits the plants or leaves to be suspended within the drying room to have free circulation of air on all sides and to thus prevent mold of the tobacco or stem rot.

From the foregoing it will be seen that 130

I have provided a machine which requires but a single operator and which is so constructed that the operation thereof is substantially continuous to thread the stems or stalks of the leaves or plants of tobacco onto a string or cord to be spaced at a predetermined distance apart and which operation requires but a single handling by the operator of the leaves or plants. Further it will be seen that the needle will be held in a stationary position while the remaining parts of the machine are permitted to have traveling movement and that the needle will be pierced through the center of the stem or stalk to thus give the greatest holding strength.

While I have herein shown and described one specific form of my invention, it will be understood that slight changes might be made in the form and arrangement of the several parts of the structure without departing from the spirit and scope of my invention, and hence I do not wish to be limited thereto except for such limitations as the claims may import.

I claim:

1. A machine for stringing tobacco comprising a piercing needle, rotating means to carry the leaves or plants to a position to be pierced by said needle, and means to hold the piercing needle against endwise and lateral displacement, and at the same time to be mechanically operated to overstep the carrying means as the leaves are threaded onto the needle.

2. A machine for stringing tobacco comprising a penetrating needle, a string connected with said needle, means to cause the leaves or plants to be pierced by said needle and strung onto said string, and mechanically operated means to engage with and hold the penetrating needle against lateral and endwise displacement, and arranged to be moved from the engagement to overstep the leaves as threaded onto the needle.

3. A machine for stringing tobacco comprising a penetrating needle adapted to have a string attached thereto, means with which the leaves or plants are engaged to be carried to said needle, means to support and hold said needle against lateral and endwise displacement and to be moved in the proper intervals to overstep the leaves and the engaging means and all of said parts so arranged that the leaf-carrying and holding means is permitted to have progressive movement while the needle is maintained at a fixed point.

4. A machine for stringing tobacco comprising means by which each of the leaves or plants is to be impaled, a plurality of holding means to receive the leaves or plants successively, rotatable means to carry said holding means and to bring said means to an operative relation, and mechani-

cally operated means to engage with said impaling means to support the same against lateral and endwise displacement and to move to the inoperative relation in the proper intervals to overstep the holding means as the leaves or plants are carried onto the impaling means.

5. A machine for stringing tobacco comprising means by which each of the leaves or plants is to be impaled, a plurality of holding means to receive the leaves or plants successively, rotatable means to carry said holding means and to bring said means to an operative relation, means within the control of the operator to cause a turning motion to be transmitted to said rotatable means, and mechanically operated means mounted to engage with said impaling means to hold the same against lateral and endwise displacement and arranged to be brought to an inoperative relation through its own mechanical means in advance of the holding means to overstep the same.

6. A machine for stringing tobacco comprising means by which each of the leaves or plants is to be impaled, an operating wheel adapted to have rotary movement, a plurality of holding fingers mounted to depend from said operating wheel to successively receive the leaves or plants and to be moved to an operative relation upon turning movement of the operating wheel, movable means to be engaged with said impaling means to hold the same against lateral and endwise displacement, and means deriving operative movement from the means rotating the operating wheel to cause said last named means to have overstepping movement to clear the holding fingers.

7. A machine for stringing tobacco comprising a penetrating needle adapted to have a string attached thereto to receive the leaves or plants and have the same held at spaced apart points throughout the length thereof, means to cause the leaves or plants to be penetrated by the needle and to carry the same to the desired points throughout the length of the string, and means to engage with said penetrating needle to hold the same against lateral and endwise displacement and to be mechanically actuated to overstep the means by which the leaves or plants are carried.

8. A machine for stringing tobacco comprising an operating wheel mounted to be capable of rotatable movement, a penetrating needle mounted adjacent the path of rotation of said operating wheel, a plurality of holding fingers connected to depend from said operating wheel and provided with notches therein through which the needle may pass during the rotation of said wheel, means engaging with said penetrating needle to hold the same against endwise and lateral displacement, and mechanical operating

means to throw said needle holding means out of operation at predetermined intervals to overstep the holding fingers.

9. A machine for stringing tobacco comprising an operating wheel mounted to be capable of rotatable movement, a penetrating needle mounted adjacent the path of rotation of said operating wheel, a plurality of holding fingers connected to depend from 10 said operating wheel and provided with notches therein through which the needle may pass during the rotation of said wheel, all of said parts so arranged that the leaves or plants may be fed successively to said 15 holding fingers and upon rotation of the operating wheel will be penetrated by and threaded over said needle, means to engage with and hold said penetrating needle against lateral and endwise displacement, 20 mechanical means for disengaging the holding means and causing the same to overstep the holding fingers as the wheel is rotated, and means within the control of the operator to cause a rotary motion to be transmitted 25 to said operating wheel to impel said wheel through its normal operative path.

10. A machine for stringing tobacco comprising an operating wheel mounted to be capable of rotatable movement, a penetrating 30 needle mounted adjacent the path of rotation of said operating wheel, a plurality of holding fingers connected to depend from said operating wheel and provided with notches therein through which the needle 35 may pass during the rotation of said wheel, all of said parts so arranged that the leaves or plants may be fed successively to said holding fingers and upon rotation of the operating wheel will be penetrated by and 40 threaded over said needle, a string connected with said needle to be received within the notches of the holding fingers and adapted to have the leaves or plants threaded thereonto and spaced apart at predetermined 45 and equi-distant points, said penetrating needle provided with openings through the body portion thereof, means to be engaged in said openings to hold the needle against lateral and endwise displacement, and means to cause said holding means 50 to be moved from the engaged relation to overstep the holding fingers.

11. A machine for stringing tobacco comprising a carrying arm mounted on a suitable support, rotatable means supported by 55 said carrying arm, a penetrating needle, a plurality of holding fingers connected with said rotatable means to receive the leaves

or plants to be operated upon, means to hold the penetrating needle at a point within the 60 path of travel of said holding fingers, cam means carried by said rotatable means to cause the needle holding means to be brought alternately into and out of operative relation to overstep the holding fingers, and 65 driving means within the control of the operator to cause movement to be transmitted to said rotatable means.

12. A machine for stringing tobacco comprising a carrying arm mounted on a suitable support, rotatable means journaled upon said carrying arm, a penetrating needle, a plurality of holding fingers connected with 70 said rotatable means to receive the leaves or plants to be operated upon and provided with notches near their lower extremities, means to hold the penetrating needle at a point within said notches to penetrate the stems or stalks of said leaves or plants, a string connected with said needle to have the 75 leaves or plants threaded thereonto, and means to be actuated by the movement of said rotatable means to cause the needle-holding means to overstep the holding fingers and the leaves or plants as threaded 80 onto the needle.

13. A machine for stringing tobacco comprising a carrying arm mounted on a suitable support, a carrying wheel rotatably mounted on said carrying arm, a penetrating 90 needle, an operating wheel connected with said carrying wheel, a plurality of holding fingers connected to depend from said operating wheel to receive the leaves or plants to be operated upon and provided 95 with notches adjacent their lower extremities, a plurality of holding means to when in an operative position engage with and hold the needle within the notches of the holding finger in a position to penetrate 100 through the leaves or plants carried therein, and means actuated from said operating wheel to cause said holding means to be brought into and out of an operative relation in a step-by-step movement to permit the 105 holding means to overstep the holding fingers and the leaves or plants as threaded onto the needle and to maintain the needle always in the stationary fixed relation.

In testimony whereof I affix my signature 110 in presence of two witnesses.

FRED J. SALZER.
